UNITED STATES PATENT OFFICE.

LOUIS SANDERS, OF NEW YORK, N. Y.

DESIGN FOR A BELT.

SPECIFICATION forming part of Design No. 33,894, dated January 8, 1901.

Application filed December 18, 1900. Serial No. 40,320. Term of patent 3½ years.

To all whom it may concern:

Be it known that I, LOUIS SANDERS, a citizen of the United States, and a resident of the city of New York, borough of Brooklyn, 5 in the county of Kings and State of New York, have invented and produced a new and original Design for a Belt, of which the following is a full, clear, and exact description, reference being had to the accompanying drawing, forming a part thereof, in which is represented a perspective view of a belt embodying the features of my design.

The features of the design consist in the downwardly-curved overlapping front terminals of the belt, which front terminals meet 15 the side portions of the belt at an angle, and

in ornaments placed at the intersection of the terminals of the belt with the body of the belt.

Having thus described my invention, I claim as new and desire to secure by Letters Patent—

The design for a belt herein shown and described.

In testimony whereof I have signed my name to this specification in the presence of two subscribing witnesses.

LOUIS SANDERS.
